(57) **CLAIM**

The ornamental design for a harness for carrying breathing apparatus, as shown and described.

DESCRIPTION

FIG. 1 is a front view of a harness for carrying breathing apparatus, showing our new design;

FIG. 2 is a rear view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view of the harness for carrying breathing apparatus in accordance with our new design.

The dotted lines are intended to show features that are environmental only and form no part of the claimed design.
